UNITED STATES PATENT OFFICE.

JAMES F. DUFFY, OF CHICAGO, ILLINOIS.

DESIGN FOR A TACK-HAMMER.

SPECIFICATION forming part of Design No. 29,984, dated January 10, 1899.

Application filed December 3, 1898. Serial No. 698,223. Term of patent 7 years.

To all whom it may concern:

Be it known that I, JAMES F. DUFFY, a citizen of the United States of America, residing at Chicago, in the county of Cook and State 5 of Illinois, have invented a new and original Design for Tack-Hammers, of which the following is a specification.

My invention relates to a new and original design for hammers, of which the following is 10 o a specification.

The drawings present two views of the design, of which—

Figure 1 is a side view, and Fig. 2 an edge view, of the same.
5 Referring to the figures, A is a long flat portion comprising a handle, at one end of which is a short portion A' at right angles thereto, comprising a head portion, and at the other end of which is a bifurcated portion A², o which may be used as a claw, but the use of which is of course immaterial to this design.

Looking at Fig. 2, the portion A will be seen to be comparatively thin and flat and in edge view to present a reverse curve, the portion a being convex downward and the portion a' 25 convex upward, giving the hammer in this view a more symmetrical and pleasing appearance than if the portion a were straight.

The characteristic features in this design are comprised in the hammer provided with 30 the comparatively thin flat portion A, curved laterally in one direction at the portion a and in the opposite direction at the portion a'.

I claim as new as desire to secure by Letters Patent—

35 The design for a hammer, substantially as shown and described.

JAMES F. DUFFY.
